[57] CLAIM

The ornamental design for an automobile radiator grill, as shown.

DESCRIPTION

FIG. 1 is a perspective view of an automobile radiator grill showing the new design;

FIG. 2 is a front elevation view thereof;

FIG. 3 is a rear elevation view thereof;

FIG. 4 is a top plan view thereof;

FIG. 5 is a bottom plan view thereof; and

FIG. 6 is a right side elevation view thereof, it being understood that the left side elevation view is a mirror image thereof.
